UNITED STATES PATENT OFFICE.

FREDERICK W. MOFFAT, OF WESTON, ONTARIO, CANADA.

ELECTRIC HEATING ELEMENT.

Application filed June 8, 1926. Serial No. 114,447.

This invention relates to elements used in the cooking tops of electric ranges.

Two types of such elements are now commonly employed, the open element in which the resistance wiring is exposed and the closed or covered type in which the resistance wiring is embedded in a refractory insulating material, which may or may not be covered with or supported by metal. The open element heats faster than the ordinary closed element and is cheaper, but the closed element gives less trouble when a pot boils over.

My object in the present invention is to devise a thoroughly reliable covered element, which will be cheaper to manufacture than the ordinary closed element and which will approximate the open element in speed of heating.

I attain my object by forming the top of the element of a flat metal disk having stiffening ribs formed on the under side. These ribs are preferably arranged to form one or more spiral grooves. In these grooves are fitted a series of blocks of porcelain or other material having the same characteristics of refractoriness and of insulating value at high temperatures. These blocks are adapted to support a coil of resistance wiring so as to effectively insulate it from the metal while interfering as little as possible with direct radiation from the wire to the metal top. A metal pan supports the metal top and contains a disk of refractory material which supports the porcelain blocks within the grooves of the top.

The device is constructed in detail substantially as hereinafter more specifically described and as illustrated in the accompanying drawings in which

Fig. 1 is a side elevation partly in section;

Fig. 2 a plan view partly in section;

Fig. 3 an end elevation of one of the porcelain blocks on a larger scale; and

Fig. 4 a plan view of the same.

In the drawings like numerals of reference indicate corresponding parts in the different figures.

1 is the top of the element, which is formed of a metal disk ribbed on its under side to form a groove or grooves. In the form of my device shown in the drawings, I show two parallel spiral ribs 2 forming two grooves. Into these grooves I insert a series of porcelain blocks 3, preferably shaped as

segments of an annulus. These blocks are frusto-conical in cross section to better fit them to the grooves which are necessarily tapered to facilitate the drawing of the pattern during the moulding of the top. Each block is formed with a longitudinal groove 4 in its upper side to receive the resistance wiring. When the blocks are all in position a substantially continuous channel for the wiring is formed. The actual contact of each block with adjacent blocks is not essential, however, as long as no gaps are left sufficient to permit of the sagging of the resistance wiring. When unsupported, each block is formed with a bridge 5, whose function is to prevent the resistance wiring springing up into contact with the metal top. These bridges are preferably as narrow as possible consistent with strength so as to interfere as little as possible with direct radiation from the resistance wiring to the top.

I have specified the blocks as being formed of porcelain, which term, however, I intend to include any material having the same properties of refractoriness and efficiency of electrical insulations at all temperatures to which it is subjected in use.

As the porcelain blocks are applied to the top from below and are not anchored to the ribs 2, it is necessary to support them in position. To support these blocks I provide the disk 6 of refractory insulating material, which is supported in the pan 7, the rim of 90 which is engaged by the rim of the top 1.

The resistance wiring is of the usually coiled type and is strung through the blocks 3 under the bridges 5. The ends of the wiring are carried downwardly through the 95 disk 6.

As in the construction shown in the drawings, there are two grooves in the under side of the top and two resistance wires. There are four wire ends brought down through the disk 6 for connection with the terminals. The terminals 8 are carried by the hubs 9 of insulating material which project through the bottom of the pan and are secured thereto. The central hub 9 has two holes formed therein, through which the adjacent ends of the resistance wires are brought for connection to the terminal, while the outer hubs have one hole each through which the adjacent ends of the resistance wires are brought 105 for connection to the terminals.

While I have shown the element as pro-

vided with two spiral grooves, it is evident that one only may be used, or any other shape of groove or arrangement of grooves known to the art.

- 5 It will be seen that an element constructed as described is superior to the ordinary closed element, in that the resistance wiring is readily renewable. This element is also a quicker heating element than the ordinary 10 closed element, in that the metal top is exposed to the direct radiation of the resistance wiring. The ribs on the under side of the top are adapted not only to stiffen the latter and prevent buckling but also serve to 15 conduct heat from the porcelain blocks to the top, thus preventing over heating of the resistance wiring and carrying the heat quickly to the upper surface of the top where it is effective for cooking purposes.
- 20 With the construction described I am enabled to employ porcelain as an insulation, which is much superior to the various cements used in the ordinary types of closed top. This construction is by virtue of its superior insulation specially adapted for use with high voltage current.

What I claim is:

1. An electric heating element comprising a metal disk ribbed to form a groove; a 30 series of porcelain blocks fitted into said groove, each block being formed with a groove to receive resistance wiring; and a bridge adapted to retain the wire in the groove, the grooves forming a substantially continuous channel for the wiring.
2. An electric heating element comprising a metal disk ribbed to form a spiral groove; a series of porcelain blocks fitted into said groove, each block being formed with a 40 groove to receive resistance wiring; and a bridge adapted to retain the wire in the groove, the grooves forming a substantially continuous channel for the wiring.
3. An electric heating element comprising a flat topped metal disk ribbed to form a 45 groove at its under side; a series of porcelain blocks fitted into said groove, each block being formed with a groove in its upper side to receive resistance wiring; a bridge adapted to retain the wire in the groove, the grooves forming a substantially continuous channel for the wiring; and a support retaining said blocks in the groove.
4. An electric heating element comprising 55 a flat topped metal disk ribbed to form a groove at its under side; a series of porcelain blocks fitted into said groove, each block being formed with a groove in its upper side to receive resistance wiring, the grooves forming a substantially continuous channel 60 for the wiring; a metal pan; a disk of insulating refractory material supported by the pan and in turn supporting the porcelain blocks; and hubs of insulating material se-

cured to and extending through the bottom of the pan and provided with holes for the passage of the ends of the resistance wiring.

5. An electric heating element comprising a flat topped metal disk ribbed to form a groove at its under side; a series of porcelain blocks fitted into said groove, each block being formed with a groove in its upper side to receive resistance wiring, the grooves forming a substantially continuous channel for the wiring; a metal pan; a disk of insulating refractory material supported by the pan and in turn supporting the porcelain blocks; hubs of insulating material secured to and extending through the bottom of the pan and provided with holes for the passage of the ends of the resistance wiring; and terminals to which the ends of the wire are connected.

6. An electric heating element comprising a flat topped metal disk; a series of porcelain blocks grooved in the upper sides and fitted end-to-end close to the under side of the disk, the grooves forming a substantially continuous channel for resistance wiring; a metal pan; a disk of insulating refractory material supported by the pan and in turn supporting the porcelain blocks; and hubs of insulating material secured to and extending through the bottom of the pan and provided with holes for the passage of the ends of the resistance wiring.

7. An electric heating element comprising a flat topped metal disk; a series of porcelain blocks grooved in the upper sides and fitted end-to-end close to the under side of the disk, the grooves forming a substantially continuous channel for resistance wiring; a metal pan; a disk of insulating refractory material supported by the pan and in turn supporting the porcelain blocks; hubs of insulating material secured to and extending through the bottom of the pan and provided with holes for the passage of the ends of the resistance wiring; and terminals to which the ends of the wire are connected.

8. An electric heating element comprising a metal disk ribbed to form a groove approximately rectilinear in cross section; a series of porcelain blocks fitted into said groove in contact with the sides thereof, each block having a groove to receive resistance wiring formed in the side facing the disk; and means for retaining the wiring in the grooves in the blocks without materially blocking radiation from the wiring to the disk, the grooves forming a channel for the wiring substantially entirely open adjacent the disk.

Signed at Toronto, Canada this 19th day of May, 1926.

FREDERICK W. MOFFAT.
